United States Patent Office.

GEORGE W. SPAULDING, OF NORTON, MASSACHUSETTS.

Letters Patent No. 63,663, dated April 9, 1867.

IMPROVED SWITCH.

The Schedule referred to in these Letters Patent and making part of the same.

Be it known that I, GEORGE W. SPAULDING, of Norton, in the county of Bristol, and State of Massachusetts, have invented a new and improved Safety Switch, of which the following is a full, clear, and exact description, reference being had to the accompanying drawings, making part of this specification, in which—

Figure 1 represents a portion of a railroad track and switch containing my improvement; and

Figure 2 is a view of the same, with the switch turned off from the main track.

The object of my invention is to prevent an engine or train of cars from running off the track by the misplacement of the switch; and the invention consists in forming a groove in the main rail or portion of the switch in such a manner as that, when the switch is misplaced, the flanges of the wheels on one side of the car or engine will enter the said groove, and be properly guided thereby to the main rail of the switch, the several parts of the switch being made of the ordinary rails used upon the road, and secured together by means of bolts, or otherwise, so that the switch can be made of material on the road at any time or place where convenient.

Referring to the drawings, *a* *a'* represent the main rail of the track, and *a b d* the portion composing the switch, supported in the usual manner at its free end on the cross-piece *g*. Fig. 1 represents the switch in proper position for the cars passing in the direction of the arrow on the main track. Near the free end of the switch on either side is a groove, *e*, in the main rail *a*, so arranged in relation to the outer bar *b* of the switch that when the latter is turned from the main track to a side track the flange of the wheel upon one side will enter the groove *e*, and thus be guided directly upon the main track *a*, thereby effectually preventing the cars from leaving the track, the opposite wheel passing upon the section *d* on the other side. The portions of the switch may all be made of ordinary rails, as used in making the track, and can be framed and put together at any of the workshops on the line of the railroad possessing the proper facilities, instead of being cast in one piece. The parts may readily be secured together in any suitable manner, and should any portion become injured or defective it may be easily removed and repaired or replaced by another piece. *f* is a guard rail, placed on the inner side of the switch, and serves as an additional means for directing the flange of the wheel upon the main track.

What I claim as my invention, and desire to secure by Letters Patent, is—

A safety switch for railroads, composed of the grooved rail *a* and the parts *b* and *d*, when constructed and operating substantially as above set forth.

In testimony whereof I have signed my name to this specification in the presence of two subscribing witnesses.

GEORGE W. SPAULDING.
